UNITED STATES PATENT OFFICE.

SELAH B. MASTEN, OF NEW YORK, N. Y.

CONCRETE-CLIP.

1,304,586.

Specification of Letters Patent. Patented May 27, 1919.

Application filed October 5, 1915. Serial No. 54,109.

To all whom it may concern:

Be it known that I, SELAH B. MASTEN, of New York, in the county of New York, and in the State of New York, have invented 5 a certain new and useful Improvement in Concrete-Clips, and do hereby declare that the following is a full, clear, and exact description thereof.

It is common engineering practice to form 10 concrete structures in which the concrete is molded around a beam, girder, channel, column, flange, angle iron, or other reinforcement. The beam or reinforcement is surrounded by a mold or form, and the concrete poured in and allowed to harden, and the mold or form then removed. In order 15 to furnish additional support to the hardened concrete and prevent it from breaking away from the reinforcement, particularly 20 at corners or where the layer is thin or not well supported by irregular surfaces, additional reinforcing means is desirable. My invention relates to such additional reinforcing means and has for its object to provide 25 a concrete clip or reinforcing device which is inexpensive to manufacture and which has advantages in use not attained in other forms of reinforcing devices. Other and further objects of my invention will be 30 apparent from the following description thereof.

For purposes of illustration, various embodiments of my invention are shown as applied to a standard I beam, but it is to be 35 understood that each embodiment shown may comprise so far as applicable any features of the other embodiments in the same or in different relation, and that the clips may be applied to any reinforcement to be 40 covered with concrete where additional reinforcing or supporting means may be utilized to advantage. As a series of clips are secured to each beam, they commonly are secured to a long wire termed a separator, 45 in order to insure that they will be spaced or separated evenly and correctly. It is an object of my invention to improve the various features of these clips, whether strung on a separator or used singly.

50 Reference is made to the accompanying drawings, wherein—

Figure 1 is a side elevation of a completed concrete structure in dot and dash outline, with an end elevation of a series of 55 standard I beams therein, on each of which

beams is attached an embodiment of my invention, and

Fig. 2 a perspective view of a standard I beam with a series of one embodiment of my invention applied thereto.

Similar reference characters refer to similar parts throughout the drawings.

The clips may be of any material and stamped, molded, or bent to shape. The drawings illustrate a simple and satisfactory method of manufacture, in which the clip is formed of wire, bent to shape. The clips may be secured to the separator by welding, soldering, weaving, or tying, or in any other desired manner. It will be noted 70 that the separator is secured to the clip in such a manner as to be adjacent the reinforcement to which the clip is secured, so that the separator will not interfere with the free flow of concrete around the reinforcement, or be liable to be displaced during any tamping or spading necessary to force the concrete in place in the form or mold.

Reference character B indicates a standard I beam to the bottom flange of which is secured a concrete clip comprising a bottom member 1, having extensions 2, and securing means 3. In the embodiment illustrated, member 1 comprises a straight wire, extensions 2 are formed by bending the wire in the shape of an eye, and securing means 3 comprise the ends of the wire which are adapted to be bent around the flange of the beam to hold the clip in place. In this embodiment it will be noted that the projections 2 are so located as to be outside of and below the flange of the I beam, to which it is attached. This places extension 2 adjacent the surface of the concrete, particularly at the corners where supporting strength is desirable, thus affording maximum support to the concrete surrounding the beam. If desired, the clips may be secured to a separator 4, which is shown in 100 this embodiment secured on the top and approximately at the center of bottom member 1.

Reference character B' indicates a standard I beam to the bottom flange of which is secured a concrete clip comprising a bottom member 11, having extensions 12, and securing means 13. In the embodiment illustrated, member 11 comprises a wire bent to approach the center of the bottom of the 110

flange, each side receding from the bottom of the flange to form extensions 12 which are formed by bending the wire in the shape of an eye, and securing means 13 comprise the ends of the wire which are adapted to be bent around the flange of the beam to hold the clip in place. In this embodiment, the bottom member 11 is so bent as not to interfere with the free flow of concrete around the bottom of the flange, or be liable to be displaced during any tamping or spading necessary to force the concrete in place in the form or mold. If desired, the clips may be secured to a separator, which is shown in this embodiment secured at the apex of the bottom member 11, as shown at 14; or in the form of a pair of separator wires on the top of each of the extensions 12, as desired.

Reference character B² indicates a standard I beam to the bottom flange of which is secured a concrete clip comprising a bottom member 21, having extensions 22, and securing means 23. In the embodiment illustrated, member 21 comprises a straight wire, extensions 22 are formed by bending the wire in the shape of what may be termed an open eye or U-shaped, and securing means 23 comprise the ends of the wire, which are adapted to be bent around the flange of the beam to hold the clip in place. This is a very inexpensive form of clip, and will be as efficient and satisfactory in some instances as the more expensive forms. If desired, the clips may be secured to a separator 24, which is shown in this embodiment secured on the top and approximately at the center of bottom member 21.

Reference character B³ indicates a standard I beam to which is secured a concrete clip comprising a bottom member 31, having extensions 32, side wires, or haunch stiffeners 33, and securing means 34. In the embodiment illustrated, member 31 comprises a straight wire, extensions 32 are formed by bending the wire in the shape of an eye, haunch stiffeners 33 extend from the extensions 32, and are integral therewith, and securing means 34 comprise the ends of the wire which are adapted to be bent around the top flange of the beam to hold the clip in place. In this embodiment it will be noted that additional support is given to the concrete by the integral side wires or haunch stiffeners 33. If desired, the clips may be secured to a separator 35, which is shown in this embodiment as comprising a pair of separator wires secured to the inside of extensions 32 so that the separator and the top of the extension will lie along the bottom face of the beam.

Reference character B⁴ indicates a standard I beam, to which is secured a concrete clip comprising a bottom member 41, having extensions 42 and 43, side members or haunch stiffeners 44, and securing means 45.

In the embodiment illustrated, member 41 comprises a straight wire, extensions 42 and 43 are formed by bending the wire in the shape of eyes, haunch stiffeners 44 extend from extensions 43 and are integral therewith, and securing means 45 comprise the ends of the wire which are adapted to be bent around the top flange of the beam to hold the clip in place. In this embodiment it will be noted that the extensions 42 and 43 are so located as to extend both outside of and below the flange of the I beam. This places the extensions adjacent the surface of the concrete, thus affording maximum support to the concrete surrounding the beam. Haunch stiffeners 44 give lateral support to the concrete.

Many modifications will be apparent to those skilled in the art, my invention not being limited to the particular embodiments disclosed to illustrate my invention, but comprising simple and inexpensive means to furnish support for the concrete in such a manner as to give maximum support, and adapted to permit the free flow of concrete into the mold or form without liability of derangement during the tamping or spading operation. The separators, for example, may be used in the relation described, in connection with other forms of extensions. Haunch stiffeners, likewise, may be provided for the embodiments applied to I beams B, B', and B², and haunch stiffeners may be omitted from the embodiments applied to I beams B³ and B⁴ and any desired form of securing means substituted as, for instance, the securing means shown in the embodiment applied to I beams B, B', and B².

Having described my invention, what I claim and desire to protect by Letters Patent of the United States is as follows:

1. A concrete clip comprising securing means, and having extensions adapted to have a substantial portion thereof extend beyond the vertical line of the part to which the clip is attached, and having additional independently formed extensions adjacent the first mentioned extensions and adapted to have a substantial portion thereof extend below the horizontal line of the part to which the clip is attached.

2. A concrete clip comprising securing means and provided with extensions having a substantial portion thereof projecting beyond the vertical line of the part to which the clip is attached, and provided with extensions having a substantial portion thereof projecting below the horizontal line of the part to which the clip is attached, and a longitudinally extending separator and tie rod lying intermediate said extensions and between said extensions and the part to which the clip is attached.

3. A concrete clip comprising securing means, and provided with extensions having

- a substantial portion thereof projecting beyond the vertical line of the part to which the clip is attached, and provided with extensions having a substantial portion thereof projecting below the horizontal line of the part to which the clip is attached, and a longitudinally extending separator and tie rod secured to a portion of said clip lying adjacent the part to which the clip is attached, whereby the formation of a pocket between said separator and said part by the application of concrete is prevented.
4. A series of concrete clips comprising securing means, extensions, and a longitudinally extending separator and tie rod connecting said clips and arranged to lie adjacent and be partly supported against upward movement by the part to which the clips are attached when in assembled relation.
5. A concrete clip having means for securing the same to the member to be concreted, extensions for said clip having their upper portions adjacent said member when in assembled position, and a longitudinally extending separator and tie rod secured to said clip adjacent said extensions with the top thereof in substantially the same horizontal plane as the top of said extensions.
6. A series of concrete clips having means for securing the same to the member to be concreted, extensions, and longitudinally extending means for separating said clips arranged contiguous and to said member so as not to interfere with the flow of concrete therearound, whereby the formation of voids or air pockets between said separating means and said member is prevented.
7. A concrete clip having means for securing the same to the member to be concreted, extensions for said clip having their upper portions juxtaposed to said member when in assembled position, and a longitudinally extending separator and tie rod adjacent to the top portions of said extensions.
8. A series of concrete clips comprising
- securing means, extensions, and a longitudinally extending separator and tie rod arranged to lie adjacent the part to which the clips are to be attached and near the outer edge thereof, whereby the formation of air pockets between said separator and said part upon the application of concrete is prevented.
9. A concrete clip comprising securing means, extensions below the horizontal line of said securing means, and means bent to form an inverted V for connecting said extensions, the top of which V is adjacent the part to which the clip is attached.
10. A concrete clip comprising extensions, securing means, and means which is bent upwardly to lie adjacent the part to which the clip is attached for connecting said extensions, and a longitudinally extending separator and tie rod at the juncture of said upwardly bent portion and said part and carried by the same.
11. A series of concrete clips comprising securing means, extensions, and a longitudinally extending separator and tie rod for said clips adapted to lie adjacent the part to which the clips are attached and near the center thereof, whereby the formation of air pockets between said separator and said part upon the application of concrete is prevented.
12. A series of concrete clips comprising securing means, extensions, and longitudinally extending separators and tie rods for said clips adapted to lie adjacent the part to which the clips are attached and near the center and near the outer edge thereof, whereby the formation of air pockets between said separators and said part upon the application of concrete is prevented.

In testimony that I claim the foregoing I have hereunto set my hand.

SELAH B. MASTEN.

Witnesses:

H. T. HENDRICKSON,
W.M. P. MILLER.

It is hereby certified that in Letters Patent No. 1,304,586, granted May 27, 1919, upon the application of Selah B. Masten, of New York, N. Y., for an improvement in "Concrete-Clips," errors appear in the printed specification requiring correction as follows: Page 3, line 34, claim 6, strike out the word "and;" same page, line 46, claim 8, for the word "concrete" read *concrete*; and that the said Letters Patent should be read with these corrections therein that the same may conform to the record of the case in the Patent Office.

Signed and sealed this 8th day of July, A. D., 1919.

[SEAL.]

R. F. WHITEHEAD,

Acting Commissioner of Patents.
